DESIGN FOR A TOY WORKBENCH

Jacob Pressman, New York, N. Y.

Application November 20, 1940, Serial No. 96,712

Term of patent 7 years

To all whom it may concern:

Be it known that I, Jacob Pressman, a citizen of the United States and a resident of the city of New York, Borough of Manhattan, in the county and State of New York, have invented the new, original, and ornamental Design for a Toy Workbench, of which the following is a specification, reference being had to the accompanying drawing forming part thereof, in which—

Fig. 1 is a perspective view of a toy workbench showing my design;

Fig. 2 is a front elevation of the toy workbench; and

Fig. 3 is a side elevation of the toy workbench.

The characteristic features of my design reside in a toy workbench having the configuration and arrangement of parts specifically as shown.

I claim:

The ornamental design for a toy workbench, substantially as shown and described.

JACOB PRESSMAN.
